CLAIM

The ornamental design for an expandable bottle, as shown and described.

DESCRIPTION

FIG. 1 is a front left side perspective view showing the new design for an expandable bottle;

FIG. 2 is a rear, right side, bottom perspective view thereof; FIG. 3 is a front view thereof, the rear, left side, and right-side views being a mirror image thereof;

FIG. 4 is a top plan view thereof;

FIG. 5 is a bottom plan view thereof;

FIG. 6 is a front left side perspective view showing the expandable bottle from FIG. 1 in a collapsed configuration;

FIG. 7 is a rear, right side, bottom perspective view thereof; FIG. 8 is a front view thereof, the rear, left side, and right-side views being mirror images thereof;

FIG. 9 is a top plan view thereof; and,

FIG. 10 is a bottom plan view thereof.

The broken lines shown in the drawings depict portions of the expandable bottle that form no part of the claimed design.

1 Claim, 10 Drawing Sheets
